UNITED STATES PATENT OFFICE

LUCY TAGLANG, OF HOBOKEN, NEW JERSEY

COMBINATION CRIB AND PLAY PEN

Application filed March 5, 1927. Serial No. 173,021.

This invention relates generally to an article of furniture in the form of a combination sleeping crib and play pen for use by a child.

The invention is in the nature of an improvement on a device of this general nature described and claimed in United States Patent No. 1,577,255, of March 16th, 1926, which covers a crib having a removable combined bedding support and floor member which can be placed in position in the framework with either the bedding or the floor side uppermost, as may be found desirable. The invention herein is for a similar organization of structure in which the combined floor member and bedding supporting structure is pivotally and permanently mounted in the framework in such manner that the structure can be reversed in position without going to the trouble of lifting the parts out of place and then restoring them to place in a reversed condition.

In addition to the pivotally mounted and reversible floor structure, to one surface of which a spring is attached, a folding chair structure of the nursery type is also included. The chair is attached to the floor structure on the side opposite that to which the spring is attached so that it may be used by a child in the relatively confined space provided by the crib side and end frame members, thereby insuring the child against falling from the chair. In order that the device may be used as a play pen, the chair may be folded into a compact relation and occupy a position flush with the inner surface of one of the end frame pieces of the structure to thereby leave an unimpeded space in which the child may play.

It will be seen that the provision of a play pen in which the floor structure is elevated from the floor of the room provides a floor space on which the child can play without risk of catching cold.

Another advantageous feature of the invention resides in the concentration into a single unit of a sleeping crib, a play pen and a chair, thereby accommodating the device for use in apartments or houses of the modern type in which the rooms are often of re-

stricted size, as well as in institutions in which a considerable number of small children are cared for.

Another feature of the invention resides in a structural arrangement of the parts which provides for folding or collapsing the device as a whole in order to reduce the bulk or size of the device and obtain a desirable compactness when the article is not in use.

Still another feature of the invention resides in the provision of a folding chair which can be completely collapsed to occupy a recess formed for the purpose in the floor member.

Other features of the invention will be hereinafter referred to.

In the drawings, in which a preferred embodiment of the invention has been selected for illustration:

Figure 1 is a view in perspective of a combination crib and play pen embodying the invention;

Figure 2 is a view in transverse vertical section of the device shown in Figure 1;

Figure 3 is a view in longitudinal vertical section of the device shown in Figure 1;

Figure 4 is a perspective view of the combined floor structure, spring unit, and folding chair used in the combination of structure embodying the invention;

Figure 5 is a sectional view on an enlarged scale of a latching device used for holding the floor structure in adjusted position;

Figure 6 is a perspective view of a locking hook structure used with the latching structure shown in Figure 5;

Figure 7 is a perspective view showing a modified combination floor member and chair structure with the chair in erected condition;

Figure 8 is a view similar to Figure 7 showing the chair in folded condition;

Figure 9 is a plan view of a form of the invention showing the device as a whole formed with a folding or collapsible structure;

Figure 10 is a perspective view of a structural detail showing the hinged connection between the chair member and the floor member;

Figure 11 is a perspective view showing

a detail of the hinged structure used in the chair construction;

Figure 12 is a view in horizontal section showing a detail of a latching mechanism used in the chair structure;

Figure 13 is a perspective view showing a detail of means for locking a spring frame member to the supporting framework.

Referring to the drawings for a more detailed description of the invention, in Figure 1 there is shown a sleeping crib structure made up of a framework including the side frame members 10 and 11 and the end frame members 12 and 13. The framework thus provided includes corner post members 14 which are provided at their lower ends with relatively small cushion tired floor wheels 15 by means of which the crib structure can be readily moved from place to place without marring polished floor surfaces.

The crib is provided with a spring and mattress structure at 16 and 16' which is supported on a floor piece 17 which substantially fills the framework of the crib. The floor piece 17 is pivoted at middle points as at 18 to the lower rails 19 of the framework so that the floor structure can be swung from a position in which the bedding is uppermost to a reversed position in which the floor structure 17 is uppermost. This capability of reversal of the floor piece 17 provides for converting the crib into a play pen at will, it being apparent that when the floor 17 is uppermost, a space is provided within the enclosing framework in which a small child can play in safety.

In order to lock the floor structure in either position, a latch member 20 is provided which consists of an elongated pin member having a finger piece 21 and adapted to be placed in position in an opening 22 provided for the purpose in the rail 23 and extending into a recess 24 in the edge of the floor member 17. Preferably a locking hook 25 is provided which is adapted to engage in a groove 26 formed in the pin 20 adjacent the finger piece 21 in order to prevent accidental removal of the pin from its latching position.

Referring to Figure 3 of the drawings, the pivotal movement of the floor member 17 about its pivotal axis is indicated, it being clear that the simple swinging of the floor member about its axis in the manner indicated will provide for the reversal of the structure from one position to the other to thereby provide for the use either of the bedding or of the play pen floor, as may be desired.

Preferably, as in the prior patent referred to, a chair structure 27 is provided. The chair is of a folding type and can be moved from its erected position, indicated in Figures 1 and 2 of the drawings, to a folded or collapsed condition, as is best indicated in Figure 4. When in the collapsed condition, the

chair occupies a position within a housing formed by a panel 35, the chair being flush with the inner surface of the end wall of the framework in an out of the way position which provides the maximum extent of space for use of the structure as a play pen.

The chair shown in Figures 1 to 4 inclusive will be seen to be made up of standards 28 which are pivoted at their free ends in the end portions 29 of slots 30 formed in the floor structure 17. The standards 28 can be folded into the slots, as indicated in Figure 4, whereupon the seat portion 31 of the chair structure occupies a vertical position with the back portion 32 folded thereagainst. Preferably the seat member 31 is provided with an opening 33, as indicated, a hinged cover member 34 being provided, as is indicated in Figure 2 of the drawings.

A modified form of chair structure is shown in Figures 7 and 8 of the drawings. The chair shown in these views is adapted to be collapsed into a flat form to fit into a recess 36 in the floor member 37. In order to achieve the completeness of collapse shown in Figure 8 the seat portion 38 of the chair is hinged at its forward edge as at 39 to the U-shaped frame member 40 which provides the legs of the chair. In addition the back portion 41 of the chair is hinged at its lower end to the seat member 38. The hinge structure provided at the two joints referred to provides for collapsing the chair into the completely flattened condition shown in Figure 8 in which the chair structure fits into the recess 36 and is flush with the outer surface of the floor member. The U-shaped frame member 40 is pivoted at its lower end to brackets 40' secured to the underside of the floor member 37, as best shown in Figure 10. The side pieces 42 of the chair may be folded against the seat when the chair is folded into the floor member.

The chair structure includes side frame pieces 42 which are hinged at 43. The frame members 42 are attached to the back member 41 of the chair by means of pins 44 which protrude through openings 45. Spring latching members 46 are mounted on the outer ends of the pins 44 and serve to lock the pins in position so as to hold the back member 41 and side frame members 42 in engaged position.

In order to provide a compact structure when the device is not in use, the framework of which the device is formed is arranged to be folded or collapsed, as is indicated in Figure 9 of the drawings. In order to bring about this advantageous feature of the invention, the end frame members 52 and 53 of the crib framework are provided with folding sections 54 which are hinged together as at 55 and hinged to the frame members 52 and 53, as at 56. This arrangement

provides for the compact folding of the framework following the tilting of the combined floor and bed structure to a vertical position, as is indicated in Figure 9 of the drawings. When folded in this manner the structure may be readily stored in a closet or some other confined space where compactness of the device is a desirable feature.

The spring structure 16 already referred to includes a frame member 47 which is removably attached to the floor plate or supporting member 17. Means for attaching the frame member to the floor member are shown in Figure 13 of the drawings in which a pin 48 and rotatable head 49 are carried by the floor member 17 and are adapted to project through a slot 50 formed for the purpose in the frame member 47. It will be seen that turning the head 49 at right angles to the length of the slot 50 provides a locking engagement of the spring supporting frame 47 to the floor member 17.

In addition to the latching structure 20, a spring latch member 51 may be provided for automatically locking the structure 17 in horizontal position when the parts have been rotated. The spring latch 51 may be manually disengaged from latching position in order to provide for rotation of the parts 20 in a counterclockwise direction, as indicated in Figure 3.

It will be seen that I have provided a combination crib and play pen of an improved construction wherein the device may be adjusted to perform different functions without the trouble and effort of lifting the floor structure from its position within the framework in order to bring about the desired reversal. The pivotal construction thus provided enables the floor structure to be readily reversed by merely removing the latching pin 20 and turning the floor structure about its pivotal point, as has been described. The replacing of the latching pin 20 in position, as indicated in Figure 5 of the drawings, securely holds the floor structure in the desired adjusted position.

What I claim is:

In a combined crib and play pen, a hollow framework, a combined bed supporting and play pen floor structure, means by which the floor structure is pivotally mounted in the framework for reversal about a horizontal axis, a foldable chair having means by which it may be folded in substantially flat formation, means pivotally mounting the chair on the floor structure and a recess in the floor structure in which the chair when folded is received and occupies a position flush with the adjacent surface of the floor.

LUCY TAGLANG.
